United States Patent Office

Des. 213,525
Patented Mar. 11, 1969

213,525

ZITHER OR SIMILAR ARTICLE

Glen R. Peterson, Jr., Summit, N.J., assignor to Oscar
Schmidt-International, Inc., Union, N.J.

Filed July 21, 1967, Ser. No. 7,944

Term of patent 14 years

U.S. Cl. D56—1
Int. Cl. D17—03

Fig. 1

Fig. 2

FIG. 1 is a perspective view of a zither or similar article, showing my new design;

FIG. 2 is a top plan view;

FIG. 3 is a side elevational view looking at the right side in FIG. 1;

FIG. 4 is an end elevational view looking at the right end in FIG. 1; and

FIG. 5 is a bottom plan view thereof.

The dominant features of my new design are shown in solid lines in the drawing.

I claim:

The ornamental design for a zither or similar article, as shown and described.
